(57) **CLAIM**

The ornamental design for a "hip bandage," as shown and described.

DESCRIPTION

FIG. 1 is a front view of the left side hip bandage.

FIG. 2 is a rear view thereof;

FIG. 3 is a side view thereof;

FIG. 4 is an inside view therof; and,

FIG. 5 is an outside view thereof.

The right side hip bandage is a second embodiment, it being a mirror image of the left side hip bandage.

The broken line showing in FIGS. 1-3 is for illustrative purposes only and forms no part of the claimed design.
